(57) **CLAIM**

The ornamental design for a bandage for a knee joint, as shown and described.

DESCRIPTION

The patent or application file contains at least one drawing executed in color. Copies of this patent or patent application publication with color drawings will be provided by the office upon request and payment of the necessary fee.

FIG. 1 is a perspective view showing my new design;

FIG. 2 is right side elevational view of FIG. 1;

FIG. 3 is left side elevational view of FIG. 1; and,

FIG. 4 is a rear elevational view of FIG. 1.
